REFRIGERATOR LINER SUPPORT

George E. Curtiss, Jr., Penn Wynne, Pa., assignor,
by mesne assignments, to Philco Corporation,
Philadelphia, Pa., a corporation of Pennsylvania

Application April 10, 1946, Serial No. 660,976

4 Claims. (Cl. 62—89)

1

This invention relates to refrigerator cabinet construction and, more particularly, to means for supporting the inner food compartment liner.

While of more general applicability, the invention is especially adapted for use in vertical type home freezers, wherein large quantities of frozen foods are stored.

As opposed to domestic refrigerators of the type intended for normal day-to-day home use wherein shelf loads are comparatively light, the storage of large quantities of frozen foods, in the freezer type, places a heavy load upon the shelves and consequently upon the liner support means. The inner liner is commonly formed of some suitable sheet metal, such as steel or aluminum. When steel is used it is usually coated with a white vitreous enamel, and care must be exercised to prevent chipping or crazing of this coating at the points of liner support. When the liner is made of aluminum, on the other hand, there is a tendency for the metal to tear at these points of support under the heavy loads carried thereby.

Another condition encountered in refrigerators normally subjected to heavy storage loads is that, if unrestrained, the side walls of the liner have a tendency to bend or buckle outwardly under the stress of the shelf loads.

Therefore, it is the principal object of the present invention to provide improved means for supporting the inner food compartment liner in a refrigerator cabinet.

More specifically, it is an object of the invention to provide for support of the liner in the cabinet and at the same time to reinforce the liner walls in a manner to prevent buckling thereof under the stress of heavy shelf loads.

It is a further object to provide such supporting means which, additionally, does not present any appreciable heat-conducting path between the outer shell and inner liner.

Yet another object of the invention resides in the provision of an improved liner supporting means, of the aforesaid type, which is further characterized by its rugged simplicity and ease of manufacture and assembly.

A preferred embodiment of the invention has been illustrated in the accompanying drawings wherein:

Figure 1 is a perspective view of a front-access vertical type home freezer embodying the invention;

Figure 2 is a fragmentary vertical sectional view taken substantially as indicated by the line 2—2 of Figure 1, the view being taken with the

breaker strip removed and certain portions broken away;

Figure 3 is an enlarged front elevational view of a fragmentary portion of the refrigerator, with the breaker-strip removed and with parts broken away to clearly illustrate details of the invention;

Figure 4 is a fragmentary sectional view, on a greatly enlarged scale, taken substantially along the line 4—4 of Figure 2; and

Figure 5 is a view similar to Figure 4, and taken along the line 5—5 of Figure 2.

With reference to the details of the drawings and particularly Figure 1 thereof, the numeral 10 designates a refrigerator cabinet having a food storage compartment 11, a door 12 for said compartment, and a machine compartment designated generally by the numeral 13.

The cabinet, as seen in Figures 2 and 3, comprises an outer casing or shell 14 within which is positioned inner liner 15. The outer shell comprises a top wall 16 and opposite side walls 17, preferably formed as a unitary structure from a single sheet of metal and to which a back wall 18 is suitably secured, as by welding. The front edge of the shell is provided with an inwardly turned flange portion 19, the purpose of which will be explained hereinafter.

Positioned between side walls 17, beneath and slightly spaced from inner liner 15, is an angle bar 20 (see Figure 2) to which is secured the top wall 21 of machine compartment 13, thus forming in the upper portion of the shell a rectangular open front compartment 22 within which is positioned, in thermally non-conductive relation with said shell, the rectangular, aforesaid open front inner liner 15 which forms the food storage compartment 11.

Rigidly secured across each front corner of compartment 22, is a gusset member 23, two of which are shown in Figure 3. Each of the top gussets has its ends suitably secured, as by welding, to the rear face of flange 19, and each of the bottom gussets has one end similarly secured to said flange while its other end is attached to one leg of angle bar 20 which leg comprises, in effect, a continuation of flange 19 and will hereinafter be considered as such.

The forward edge of inner liner 15 is provided with an outwardly extending flange portion 24 which, when the liner is positioned in the shell, is in substantially coplanar relation with flange 19 of outer shell 14, thus facilitating the attachment of a suitable breaker-strip 25 (Figure 1) to close the gap therebetween.

Securely attached to the front face of each of

the gussets is a thermally nonconductive element 26 to which the corners of liner flange 24 are attached by screws 27, whereby to support the liner in spaced relation within the shell in a manner preventing direct heat flow from the shell to the liner. The gusset members are each formed with an indented central portion 28 to provide room for insulating element 26 while still maintaining the coplanar relation of flanges 19 and 24.

In the usual two-temperature domestic refrigerator intended for day-to-day storage of perishable foods the above-described liner support may prove to be sufficient, as shelf loads under these conditions are relatively light. However, as explained hereinabove, in the type of refrigerator adapted for storage of frozen food, the shelf loads are heavy and provision of adequate support for the liner becomes a problem. Then too, as stated above, liners are usually constructed of comparatively thin material, such as sheet metal, and heavy shelf loads may tend to force the side walls of the liner outwardly.

Therefore, in particular accordance with the present invention, provision is made for rugged and adequate liner support, while at the same time eliminating any possibility of bending or buckling of the liner. To this end, a pair of support members are employed, each disposed along one side wall of the liner in the space between said liner and the outer shell. One of these members has been illustrated at 29, in Figure 3, and it will be understood that an identical construction is provided at the opposite side of the cabinet. Each of the members 29 comprises a rigid element, preferably in the form of an angle bar having its ends 30 attached to the rear face of each pair of upper and lower gussets 23. Suitable nonconductive members 31 (Figure 2) are arranged between the ends of the members 29 and said gussets, and serve to prevent the flow of heat from casing 14 to said bar or member.

As seen in Figures 2 and 3, the side walls of liner 15 are attached to angle bar 29 at points intermediate the top and bottom corners thereof and in a plane rearwardly offset from the plane of flanges 19 and 24. This is accomplished by screw and stud assemblies designated generally by the numerals 32 and 33. The assembly 32 is illustrated more clearly in Figure 5 and will now be described with particular reference thereto.

In this figure it is seen that a thermally nonconductive or insulating element 34 is securely attached, as by screws 35, to angle bar 29 and is provided with a central bore 36 axially aligned with an aperture 37 in liner 15 and a co-centered aperture 38 in bar 29, both of which are of larger diameter than said bore 36. Element 34 has a thickness equal to the dimension of the space between the bar 29 and the side wall of the liner, and carries (within bore 36 thereof) a screw 39 upon which is mounted a hollow shelf-supporting stud 40. The stud 40 is provided with axially extending radially offset fingers 41 which extend through aperture 37 into a recess 42, provided in the face of insulating element 34. These fingers are flexed upwardly, as by screw 39, to a position behind and against the periphery of said aperture, thereby maintaining the elements as a unitary rigid structure when the screw is fully engaged.

It will be noted that the heads of screws 35 are countersunk beneath the surface of insulating element 34, and that the outside diameter of the threads on screw 39 is less than the diameter of

aperture 38, thus preventing any direct metal-to-metal contact between the liner and angle bar 29 through which heat might flow from one to the other.

As brought out above, the structure illustrated in Figure 3 is duplicated on the opposite side of liner 15, as shown in Figure 2. The opposing studs 40 provide the means for supporting the front portion of a shelf 43 which, as illustrated, comprises a frame 44 adapted to rest upon said stud and which has a plurality of cross wires 45 upon which the food is placed.

The rear portion of the shelf may be supported in any convenient manner, but, by way of illustration, is shown as supported upon a screw and stud construction somewhat similar to that which supports the front portion of the shelf. The screw 46 is passed through the stud 47 and threaded into a speed nut 49, formed as a U-shaped clip and frictionally carried by a Z-shaped bracket 48 suitably secured to the liner 15.

An evaporator 48 is positioned in the upper portion of the food compartment liner, said evaporator being secured to the liner and angle bar in a manner similar to that just described with reference to the shelf supporting lugs 40 and 47.

Studs are unnecessary at this point, as the bottom wall of the evaporator comprises the food-carrying shelf and, therefore, screws 39a and 46a are passed through an aperture in the evaporator wall, and through registering apertures 37a in liner 15, and drawn up tightly into threaded engagement with insulating element 34a and speed nut 49a, respectively.

Thus it is seen that the invention provides two additional points of suspension or support, on each side wall of the liner, while at the same time reinforcing the said walls against buckling under the stress of heavy shelf loads. However, it should be understood that two points have been shown by way of illustration only, and that any desirable number may be used, according to the liner capacity. It should also be clearly understood that additional points of support may be provided at positions along the wall not associated with the shelving or evaporator.

A particular feature of the invention resides in the fact that it provides additional support and reinforcement for the liner in a manner avoiding the danger of additional heat loss, because there is no direct metal-to-metal contact between the liner and the shell.

I claim:

1. A refrigerator cabinet construction comprising a substantially rectangular open front casing, a substantially rectangular open front inner food compartment liner disposed within said casing in spaced relation therewith, an evaporator disposed within said liner, a support positioned in each corner of said casing, means for securing the corner portions of said liner to said members in thermally non-conductive relation therewith, liner support means carried by said members, and apparatus connecting said support means in thermally non-conductive relation with both said liner and said evaporator for supporting said liner and said evaporator within said shell.

2. A refrigerator cabinet construction comprising a substantially rectangular open front casing, a substantially rectangular open front inner food compartment liner disposed within said casing in spaced relation therewith, an evaporator disposed within said liner, a gusset positioned

across each corner of said casing, means for securing the corner portions of said liner to said gussets in thermally non-conductive relation therewith, a pair of rigid elongate bar members each positioned adjacent and parallel with a side of said liner in spaced relation therewith, each of said bar members having its opposite ends attached in thermally non-conductive relation to opposed upper and lower gussets, each of said bar members carrying an insulating block disposed in the space between the bar member and inner liner, and means for securing said liner and said evaporator to said insulating blocks.

3. A refrigerator cabinet construction comprising a substantially rectangular open front casing, a substantially rectangular open front inner food compartment liner disposed within said casing in spaced relation therewith, a support bracket positioned in each corner of said casing, insulating means secured to each of said support brackets, means securing corresponding corner portions of said liner to said insulating means, a pair of vertically positioned elongate support elements each having its opposite ends connected in thermally non-conductive relation to opposed upper and lower corner support brackets, each of said elongate support elements carrying an insulating member and each being disposed adjacent said inner liner and spaced therefrom, each of said insulating members comprising an elongate block of insulating material secured at opposite end portions thereof to said support element, and means for securing said inner liner to an intermediate portion of each of said blocks and in thermally non-con-

ductive relation with said elongate support elements.

- 5 4. A refrigerator cabinet construction comprising a substantially rectangular open front casing, a substantially rectangular open front inner food compartment liner disposed within said casing in spaced relation therewith, an evaporator positioned within said liner, a support bracket positioned in each corner of said 10 casing, insulating means secured to each of said support brackets, means securing corresponding corner portions of said liner to said insulating means, a pair of vertically positioned elongate support elements, each having its opposite ends connected in thermally non-conductive relation to opposed upper and lower corner support brackets, each of said elongate support elements carrying an insulating member and each being disposed adjacent said inner liner and spaced therefrom, and means for securing said inner 15 liner to said insulating members and in thermally non-conductive relation with said elongate support elements, said last means also serving to secure said evaporator within said inner liner.
